UNITED STATES PATENT OFFICE.

ANDRÉ F. BORNOT, OF PHILADELPHIA, PENNSYLVANIA.

MACHINE FOR SCOURING GARMENTS, FABRICS, &c.

No. 812,005.

Specification of Letters Patent.

Patented Feb. 6, 1906.

Application filed January 9, 1904. Serial No. 188,887.

To all whom it may concern:

Be it known that I, ANDRÉ F. BORNOT, a citizen of the United States, residing in the city and county of Philadelphia, State of Pennsylvania, have invented a new and useful Improvement in Machines for Scouring Garments, Fabrics, &c., of which the following is a specification.

My invention consists of a machine for scouring or cleansing garments, fabrics, &c., embodying novel features as will be herein-after described, and pointed out in the claims.

Figure 1 represents a vertical section of a scouring-machine embodying my invention. Fig. 2 represents a top view of a portion thereof. Fig. 3 represents a perspective view of an interior member thereof. Fig. 4 represents a transverse section taken through the fastening devices of the cover and body of the machine and through said cover beneath said devices.

Similar letters of reference indicate corresponding parts in the figures.

Referring to the drawings, A designates a cylindrical tank, and B designates a rumble within said tank and being mounted thereon by means of the journals C, said rumble being preferably of triangular form and having its body constructed of a peripheral portion of closely-adjoining slats D and sides formed of heads E, to which said slats are firmly secured, said slats being fitted closely to each other and having their inner surfaces corrugated, as at F, the periphery of the rumble being continuous, unbroken, and imperforate or solid, whereby it is enabled to endure the severe strain to which it is subjected by the blows of the garments or fabrics in the rumble due to the overturning and dropping of said contents when the machine is in operation, as will be hereinafter more fully set forth, and the scouring fluid employed will not escape at said periphery, and so it will act effectively on said garments or fabrics. In the sides or heads E are perforations G, whereby the interior of the tank or vessel A and that of the rumble B are in communication.

H designates the lid of the rumble, the same being formed of slats H', fitted closely to each other, and cleats or braces J, to which the ends of said slats are bolted or otherwise secured, the inner sides of said slats being corrugated, as at F', and forming with the interior sides of the body of the rumble an unbroken continuity. The lid H is hinged to the body of the rumble by means of the ears

K on the cleats J and ears L on the braces M of the rumble, said ears K L thus being connected in a strong manner with the respective lid and body through the medium of said braces J M. Passing through the ears K L is the rod N, which thus forms the hinge or axis of the lid H and permits the latter to be raised and lowered, and so opened and closed. The ends of the cleats J opposite to the rod N are formed with ears P, and the braces M are formed with ears Q, being coincident and receiving the sliding bolts R, which are freely fitted in the ends of a tube or tubular casing R', the latter extending transversely over the lid H and containing the spring S, which presses outwardly against said bolts to hold the same, and consequently the lid, firmly in closed position, said bolts being provided with knobs R², movable in the slots R³ in said tube R' for evident purposes.

On the terminals of the cleats J next to the bolts R are lips T, which extend forwardly from the ears P and rest on the adjacent portion of the exterior of the body of the rumble for purposes to be hereinafter explained.

U designates the lid or cover of the tank or vessel A, the same being hinged to the latter by means of the ears V on said cover and ears W on the body of said tank and the bolt X, which passes through said ears V and W. The wall of the opening in the tank A occupied by said cover U is rabbeted or shouldered, as at Y, and has the adjacent edge portion of the cover U resting thereupon. Screws Z rise from the wall of the tank A, outside of the same, and are engaged by oblong thumb-nuts A', which in one position have their under sides or bases overlap the edge portion of the lid or cover U, whereby when said nuts are tightened said lid is pressed firmly against said rabbet or shoulder Y and produces a tight joint at the contiguous parts, it being evident that when the nuts are somewhat unscrewed—say a quarter of a turn—their under sides are removed from the upper portion of the cover U, when the latter may be swung upwardly on its axis X, and thus open the tank or vessel A, permitting access to the interior thereof.

In order to hold and press down the other sides of the cover U, I employ the screws B' and nuts B², whose bases are sufficiently wide to overlap the adjacent edge portion of the cover U, it being noticed that said portion is formed with a rabbet or shoulder C', against which the edge portion of the lid or cover U

rests, so that when the nuts B² are properly turned the lid will be held firmly against the rabbet or shoulder Y, producing a tight joint and preventing leakage therat.

5 The operation is as follows: The lid U is opened, thus permitting access to the interior of the tank A, and the lid H is also opened, permitting access to the interior of the rumble. The garments or fabrics to be scoured 10 or cleansed are then placed in said rumble, when the lid H is closed and secured, a proper quantity of benzene or other scouring or cleansing fluid having been placed in the tank A. The lid or cover U is also restored to its 15 closed position and tightened, when rotary motion is imparted to the rumble by means of the pulley or crank-arm on either journal thereof or by any other suitable means, it being seen that owing to the perforations G the 20 fluid in the tank enters the rumble, and so acts upon said garments or fabrics, which latter are carried around by the rumble and tumbled, overturned, and agitated while being subjected to a beating action on the 25 corrugated inner face of the rumble, and thus the work of scouring or cleansing will be effectively performed, it being noticed that the benzene, which is of a volatile nature, is prevented from escaping through the cover 30 of the tank, owing to the tightening means employed therefor. When the lid or cover H is in the position shown in Fig. 3, the lips T, which extend from the ears P on said lid, rest solidly on the adjacent portion of the 35 body, thus limiting the inward motion of the lid and relieving the bolts R of strain, while also locating the ears P and Q so that their openings register for the proper entrance of the bolts R into the same, it being also 40 noticed that while the lid is adapted to rest on the top portion of the brace M comprising the wall of the opening of the body when said lid in closing drops on said wall the lips J drop upon and abut against the adjacent slat 45 of the body, and so take portion of the blow and strain of the lid on its seat. Again, when the lid is to be opened a pry may be placed

under said lips to start the opening of the lid, the effect of which is evident.

Various changes may be made in the details of construction shown without departing from the general spirit of my invention, and I do not, therefore, desire to be limited in each case to the same. 50

Having thus described my invention, what I claim as new, and desire to secure by Letters Patent, is—

1. In a scouring-machine of the character stated, a rumble consisting of a body, a closing-cover for the inlet thereof, braces around said body, longitudinally-extending braces on said cover, pairs of ears respectively at the pivotal and free ends of said cover, the members of each pair of ears having registering openings therein, an axial bolt passing through the ears at the pivotal end of said cover, securing-bolts passing through the ears at the free end of said cover and a tubular casing extending transversely over the cover and containing said securing-bolts. 60 65 70

2. In a scouring-machine of the character stated, a rumble consisting of a body, a closing-cover for the inlet thereof, braces on said body and cover respectively, ears continuous of the braces of the body, ears continuous of 75 the braces of the cover and a fastening device in the adjacent ears of the cover and body.

3. In a scouring-machine of the character stated, a rumble consisting of a body, a closing-cover for the inlet thereof, braces on said body and cover respectively, ears continuous of the braces of the body, ears continuous of the braces of the cover, said ears having registering openings, fastening devices for the 80 85 cover in said openings, and lips extending forwardly from the cover and continuous of the ears thereof and adapted to overhang the adjacent portion of the body and rest thereupon.

ANDRÉ F. BORNOT.
